GLUE JOINT APPARATUS

Filed April 17, 1922

2 Sheets-Sheet 2

UNITED STATES PATENT OFFICE.

GEORGE LITTLEFORD, OF FORT THOMAS, KENTUCKY.

GLUE-JOINT APPARATUS.

Application filed April 17, 1922. Serial No. 553,599.

To all whom it may concern:

Be it known that I, GEORGE LITTLEFORD, a citizen of the United States, residing at Fort Thomas, in the county of Campbell and State of Kentucky, have invented certain new and useful Improvements in Glue-Joint Apparatus, of which the following is a specification.

My invention relates to improvements in glue-jointing apparatus. One of its objects is to provide improved apparatus to assemble and glue together a plurality of relatively narrow strips to form wide composite boards to serve as table tops, desk tops, and for similar purposes. Another object is to provide such improved apparatus adapted to more quickly assemble and unite such strips together. Another object is to provide improved apparatus adapted to assemble strips of slightly different thicknesses so as to automatically present when assembled one plane face and one irregular face. Another object is to provide improved apparatus to assemble such strips into composite boards which will require a minimum cut to face the respective sides of the composite boards. Another object is to provide improved apparatus to assemble strips which are slightly warped, of different thickness, or otherwise irregular to provide composite boards with a minimum of waste material. Another object is to provide strip assembling apparatus to apply a substantially uniform pressure to the respective strips irrespective of the thickness of the strips. My invention also comprises certain details of form, combination and arrangement, all of which will be fully set forth in the description of the accompanying drawings in which:

Fig. 1, is a side elevation of a glue jointing apparatus embodying my invention.

Fig. 2, is a perspective view of a composite board and my improved apparatus employed to assemble the same.

Fig. 3, is a sectional detail taken on line 3-3 of Fig. 2.

Fig. 4, is a plan view of the detached assembling apparatus shown in Fig. 3.

Fig. 5, is a sectional detail taken on line 5-5 of Fig. 3.

Fig. 6, is a perspective view of one of the clamping or draw bars detached.

Fig. 7, is a perspective view of a portion of a detachable lever employed to apply initial pressure to the assembled strips.

The accompanying drawings illustrate the preferred embodiment of my invention, in which 15 represents a supporting frame carrying two axles 16 and 17 on which are mounted sprocket wheels 18 and 19 and an endless belt 20 to which are attached a series of stock supporting or clamping frames 21, which are usually employed in groups of two or more to each series of strips to be assembled and clamped together. Mounted at one end of the frame 15 is a weighted and rocking support 22 adapted to be tilted into and out of the path of the free ends of the clamping frames 21 and to act as a support for the extended ends of a series or set of members 21 while the series of strips are being assembled and clamped together.

In practice while the respective strips to be assembled are designed to be cut to a uniform thickness, they are, due to shrinkage warping and a variety of other causes, not of uniform thickness when assembled to be united into wide composite boards. Also some of said strips are curved slightly from end to end or slightly twisted from end to end making it difficult to assemble said strips so as to present comparatively plane or smooth faces or faces which will not require excessively deep facing cuts to reduce them to finished plane faces. Also in assembling any attempt to hammer or locally press the strips into place results in a corresponding displacement of the strips at other portions of their length and the adjustment of one strip into place results in a corresponding displacement of another strip.

In order to cause the strips to automatically assume relative positions most nearly approaching a composite board having one plane face, or positions which will produce composite boards requiring minimum waste and minimum finishing cuts to attain substantially parallel finished faces on opposite sides of the composite boards I provide a plurality of supporting or clamping frames 21, usually from two to four or five depending upon the size or length of the strips to be united. Said clamping frames may be mounted pivotally upon cross bars 24 attached to the links of

sprocket chain 20, or if desired attached to the hub of an axle like the spokes of a wheel, where a less number of composite boards are required within a prescribed length of time. The frames 21 may also be separately employed and assembled upon cross rails where a small quantity only of composite boards are required.

As shown in Fig. 1, the rocking member 22 serves to support the free ends of a series of frames 21 while the wooden strips 25 with glue applied to their meeting edges are assembled loosely upon the upper faces of the frames 21 and with one strip in contact with the series of clamping faces 26 at the free ends of the frames 21. The clamping members 27 are then fed by a coarse ratchet feed along the frames 21 until they contact with the edge of the strip at the opposite side of the composite board. A series of bars 28 each having a series of spring actuated plungers 29 are then adjusted into place relative to the several frames 21 to press the individual strips 25 into alignment upon the frames 21 and to hold said strips in place upon the several frames 21, while the clamping members 27 are drawn with a slow feed clamping pressure against the assembled strips and toward the clamping faces 26 to insure close contact of the several strips at their meeting edges and strong practically invisible joints. The clamping apparatus and composite boards are then released by the rocking member 22 and the chain 20 fed forward to bring a new series of frames 21 into position to receive a set of strips 25, while the strips previously assembled are allowed to remain in their assembled and clamped position in the frames 21 until the glue joints have become firmly set after which the clamps are released and the composite boards removed.

The length of the chain 20 is to be suited to the capacity of the particular factory to be served, so that the clamped frames in moving along the under portion of the chain from the axle 19 to the axle 18 will afford sufficient time for the glue joints to become firmly set, and at the same time allow sufficient stock to be clamped up to meet the requirements of the factory.

The respective frames 21 are preferably composed of angle bars 30 and 31 united at one end to a casting 32 provided with a clamping face 26, a recess for the passage of the threaded shank 33 and a latch member 34 pivotally mounted thereon at 35. At their opposite end the angle bars 30 and 31 are united to a casting 36. The casting 36 is provided with recesses 37 to receive the tie rods 24. To the castings 36 are connected the rocker arms 38 by means of pivot bolts 39. The rocker arms 38 are each provided with a socket 40 to receive one end of a bar 28; at the opposite ends of the rocker

arms 38 are connected one end of springs 41, while the opposite ends of springs 41 are connected to eyes 42 of the castings 36, thereby tending to hold the socket ends of the rocker arms 38 in elevated position, which is 70 the most convenient position for the insertion of the ends of the bar 28 into said sockets.

Each of the bars 28 is provided with a series of recesses 43 in which are mounted 75 a series of plungers 29, each provided with a head 44 at one end and a pair of lock nuts 45 and 46 at the opposite end. Each plunger has a limited movement transversely relative to the bar 28, and is energized by means of 80 a coiled spring 47 encircling the shank of the plunger between its head 44 and the bar 28. Each bar 28 is preferably provided with an offset end 28' to be engaged by the latch 34, and also preferably with a cross-bar 48 85 adapted to be engaged by a detachable forked lever 49 to enable manual pressure and leverage to be employed to force the forward ends of the bars 28 toward the frames 21 until the latches 34 are enabled to 90 engage and lock over the ends 28' of the bars 28.

Each of the threaded shanks 33 is provided with a perforated bar 50 which passes through and is supported and guided by a 95 recess in the clamping member 27. Each clamping member is provided with a finger or pawl 51 spring actuated to normally tend to engage one of the perforations 52 of the bar 50. When the hand lever end of the 100 pawl 51 is pressed toward the clamping face of the member 27 the pawl 51 and member 27 are released from the bar 50 and may be adjusted by hand along the frame 21. When the pawl 51 is latched to bar 50 a hand 105 actuated nut 54 threaded to the shank 33 outside of the casting 32 enables the clamping member 27 to be drawn with a screw feed firmly toward the clamping face 26 to firmly clamp the assembled strips together. 110 Slots 55 are preferably provided in the members 27 opposite and for passage of the heads 44.

It will be noted that the series of yieldingly energized plungers 29 acting at intervals along each of the assembled strips 25 and before any clamping pressure has been applied to the edges thereof tends to cause each strip to assume and retain a position as nearly in contact as possible with the plane face of all the angle bars 30 and 31, and hence to bring one face of all of the strips 25 into and retain them in substantially one plane throughout the act of clamping the strips edgewise into one composite 120 board, and until the glue has fully set. The yielding plungers are spaced sufficiently close together so that at least one plunger from each bar 28 bears upon each strip of wood. The bars 28 are conveniently detach- 130

able and adapted to be employed interchangeably to facilitate assembling and removing the stock members.

The apparatus herein shown and described is capable of considerable modification without departing from the spirit of my invention.

What I claim is:

1. A glue press apparatus comprising a stock supporting member adapted to support a plurality of stock members to be united side by side, and transversely thereof at a plurality of points of support intermediate of their lengths, a plurality of resiliently energized plungers to independently engage the respective stock members at a plurality of points intermediate of their lengths to press the stock members individually into contact with the stock supporting member, means to support said plungers in relation to the stock supporting member, and means to press the stock members into mutual engagement at their glue points while assembled and under pressure from said plungers to unite said individual stock members into composite stock members.
2. A glue press apparatus comprising a stock supporting member adapted to transversely support a plurality of stock members to be united side by side and at a plurality of points of suspension intermediate of their length, a plurality of presser bars each provided with a plurality of resiliently energized plungers spaced thereon to independently engage the respective stock members to individually and yieldingly press said

stock members into contact with the stock supporting member at a plurality of points intermediate of the length of said stock members, means to detachably hold said presser bars in fixed relation to the stock supporting member, and means to press said individual stock members into mutual engagement at their glue joints while assembled and under yielding pressure from said plungers to unite said individual stock members by glue joints into composite stock members.

3. A glue press apparatus comprising a plurality of stock supporting members arranged in substantially one plane and adapted to rigidly support a plurality of individual stock members transversely thereof and intermediate of their ends, a plurality of presser bars each provided with a plurality of resiliently energized plungers to independently engage the respective stock members to independently yieldingly press the stock members into engagement with said respective supporting members, means to detachably hold the respective presser bars in fixed relation to said supporting members, and means to press the glue joint edges of said individual stock members into mutual engagement while said stock members are assembled and yieldingly held by said plungers in engagement with said supporting members.

In testimony whereof I have affixed my signature.

GEORGE LITTLEFORD.
